UNITED STATES PATENT OFFICE.

PERCIVAL S. TICE, OF WASHINGTON, DISTRICT OF COLUMBIA.

CARBURETER-GOVERNING DEVICE.

1,321,261.

Specification of Letters Patent. Patented Nov. 11, 1919.

Application filed May 10, 1917, Serial No. 167,787. Renewed May 1, 1919. Serial No. 294,097.

To all whom it may concern:

Be it known that I, PERCIVAL S. TICE, a citizen of the United States, residing at 715 Webster street northwest, Washington, D. C., have invented new and useful Improvements in Carbureter-Governing Devices, of which the following is a specification, reference being had to the accompanying drawings, forming a part thereof.

10 The purpose of this invention is to provide improved means for governing the air supply to a carbureter for an internal combustion engine. It consists in the elements and features of construction shown and described, as indicated in the claims.

In the drawings, the sole figure is a partly sectional view of a side elevation of a carbureter equipped with this invention, section being made axially with respect to the 15 air inlet and the valve therein.

The drawing shows in conventional or customary form the float chamber, A, of a carbureter, from which the liquid fuel is discharged through a nozzle, B, into a Venturi tube or constricted throat-way, C, of the suction passage, D, leading to the engine intake (not shown). The suction passage has the air inlet encompassed by a valve seat, 2, facing inwardly, seating the valve, 3.

20 This valve is a hollow or chambered body, most conveniently cylindrical in outline, having its chamber, 3^a, opening inwardly toward the suction passage; and it is mounted for guidance in its movement toward and 25 from its seat on a stem, 4, which projects inwardly from a bridge, 5, extended across the air inlet. Rigid with the inner end of this stem, 4, there is a head, 6, which being rigid with the stem is thereby rigid with the valve.

30 seat, and which is positioned in the open inner end of the chambered valve, and is adapted to operate piston-wise therein in the opening and closing movement of the valve. A spring, 7, reacts between the head and the 35 body of the valve for normally seating the valve by the action of the spring, and resisting its opening by the suction. The stem, 4, is axial hollow, and the duct, 4^a, therein is continuous from a duct, 5^a, in the bridge,

40 5, said bridge, as illustrated, having an axially positioned boss, 5^b, in which also the duct extends, opening radially therefrom for the purpose of controlling the exterior end by a valve member, 8, mounted upon the

protruding boss, 5^b, of said bridge, having 55 an aperture, 9^a, for registering with the radially opening end of the duct, and adapted to be rotated on said projection for varying the opening, or closing it entirely. A spring, 11, reacting between a washer, 12, on the 60 end of a stem, 13, which projects from said axial boss, 5^b, of the bridge, and a second washer, 14, which bears against the outer end of said valve member, operates to keep the valve snug on its seat, which is tapered 65 to further assist this result. The duct, 4^a, in the stem, 4, opens into the piston chamber of the valve, as seen at 4^b. The head or piston, 6, is constructed for limited leakage past it from the piston chamber, 3^a, of the 70 valve, 3, into the suction passage, D, which leakage may be effected either by having said piston head slightly loose in the piston chamber, or by providing it with a small aperture, 15, as shown, or both. Since, as 75 will be understood, the valve is definitely and accurately carried on the stem, 4, and does not rely upon the piston for its guidance, it is practicable to make this piston a sufficiently loose fit to insure limited leakage, and the advantage of obtaining the leakage in this manner is that at the same time the frictional resistance to the valve movement, which would be caused by a snug fitting piston, is avoided.

80 The operation of the above described structure is as follows:—

The parts being in the position shown in the drawing, the valve 3, operating as the throttle valve of the carbureter, remains 85 upon its seat when the engine is started, notwithstanding the partial vacuum created by the engine suction in the passage, D, because the admission of atmospheric pressure through the ducts, 5^a and 4^a into the chamber 3^a, of the valve, equalizes the pressure upon opposite sides of the valve. Under this condition of operation, which corresponds to very slow rotation of the engine crank, as in the idling of the engine, air 90 flowing from the exterior through the continuous ducts 5^a, 4^a, and aperture, 4^b, into the chamber, 3^a, of the valve, 3, passes also to a small extent past the piston, 6, by virtue of the leakage provided either around 95 the working edge of the piston or through the aperture, 15. This leakage being very much less than the capacity of the passages

by which the atmospheric pressure is admitted to the chamber, 3^a, does not effect any material reduction of the pressure in the chamber, 3^a, below atmospheric, and 5 the valve is held seated under the action of the spring. The valve, 8, being adjusted to restrict the air inlet through the ducts, 5^a and 4^a, to the chamber, 3^a, the pressure in that chamber will be reduced below 10 atmospheric, and such air inlet being reduced sufficiently by the adjustment of the valve, 8, the pressure in the chamber, 3^a, will become lowered by the leakage past the piston, 6, until the excess of atmospheric pressure 15 on the outer face of the valve over the reduced pressure within will be sufficient to overcome the resistance of the spring, 7, so that the valve will be opened by the atmospheric pressure to greater or less extent, dependent 20 upon the degree of suction operating in the suction passage, D, and the extent to which the air access through the ducts, 5^a 4^a, is restricted by the adjustment of the valve, 8; and when the chamber, 3^a, is completely 25 shut off from communication with the atmosphere by the complete closing of the valve, 8, the pressure within the chamber, 3^a, will be reduced to that existing in the suction passage, D. The spring, 7, is designed to 30 be of such stiffness that under these conditions the valve, 3, will be wide open. It will be understood that one function of the spring, 7, is to maintain within the suction passage, D, such degree of pressure lower 35 than atmospheric as to be adequate to supply the carbureter with the liquid fuel by the suction of the engine. When the valve 3, is open to any extent, the suction in the passage, D, is reduced,—that is, the pressure 40 is raised,—by reason of the entrance of the air past the valve, and the leakage past the piston is reduced. At any given degree of opening of the valve, 8, equilibrium between 45 the internal and external pressure on the valve, 3,—including in the internal pressure of the resistance of the spring, 7,—will be attained at a certain degree of suction in the passage, D; and the degree of suction being dependent upon the speed of the engine, it 50 follows that the degree of opening of the valve, 8, will substantially determine the engine's speed.

It will be noticed that the relation of the chambered valve, 3, to the fixed piston member, 6, is substantially that of the two members of a dash-pot when considered with relation to the action of the valve under any force tending to open it, and the device does in fact act as a dash-pot, in tending to 55 steady the action of the valve and prevent it from fluttering or yielding too sensitively to rapid variations in the suction, which may result from sudden changes of speed of the engine.

The construction shown in this application is a development from a fundamental invention which is common to this application and my pending application No. 127,233, filed October 23, 1916; and this fundamental invention, common to both the applications, is claimed in its broader phases in my said earlier application, and the broad claims for that invention are not made in this application.

I claim:—

1. In combination with a suction passage having an air inlet, a valve controlling said inlet opening inwardly, said valve having a piston chamber opening inwardly; a head fixed with respect to the valve seat positioned in said piston chamber and acting piston-wise therein in the opening and closing movement of the valve, said head being constructed for affording limited leakage past it from the piston chamber into the suction passage; a conduit leading from the outer air into said piston chamber, and means for controlling the air access to said conduit.

2. In combination with a suction passage having an air inlet, a valve controlling said inlet opening inwardly; said valve having a piston chamber opening inwardly; a head fixed with respect to the valve seat positioned in the said piston chamber and acting piston-wise therein in the opening and closing movement of the valve, said head being constructed for affording limited leakage past it from the piston chamber into the suction passage; a stem fixed with respect to the valve seat, affording guidance for the valve and extending into said chamber, said stem having an air duct leading from the outer air into said chamber, and means for controlling the air access to said air duct.

3. In combination with a suction passage having an air inlet, a valve controlling said inlet and opening inwardly, said valve having a piston chamber opening inwardly; a head fixed with respect to the valve seat, positioned in said piston chamber and acting piston-wise therein in the opening and closing movement of the valve, said head being constructed for affording limited leakage past it from the piston chamber into the suction passage; a conduit leading from the outer air into said piston chamber; means for controlling the air access into said chamber, and a spring in the chamber re-acting between the valve and said head for resisting the opening movement of the valve.

4. In combination with a suction passage having an air inlet, a valve controlling said inlet and opening inwardly; a bridge across said inlet and a stem extending from said bridge for guidance of the valve in its movement toward and from its seat; a head fixed with respect to the valve seat positioned in

- said piston chamber and acting piston-wise therein in said opening and closing movement, said head being constructed for affording limited leakage past it from the piston chamber into the suction passage; said bridge and stem having ducts leading from the outer air into the piston chamber of the valve; and exteriorly-accessible means for controlling air access to said duct.
- 10 5. In combination with a suction passage having an air inlet; a spring-seated valve controlling said inlet and opening inwardly, said valve having a piston chamber opening inwardly; a head fixed with respect to the valve seat, positioned in said piston chamber and acting piston-wise therein in the opening and closing movement of the valve, the head being constructed for affording limited leakage past it from the piston chamber into the suction passage; a conduit leading from the outer air into said piston chamber, and exteriorly-accessible means for controlling the air access to said conduit.

In testimony whereof, I have hereunto set my hand at Detroit, Michigan, this 5th day of May, 1917.

PERCIVAL S. TICE.
